UNITED STATES PATENT OFFICE.

JOSEPH C. MYERS, OF COLONIE, NEW YORK.

WINDOW-SASH.

1,258,432.

Specification of Letters Patent.

Patented Mar. 5, 1918.

Application filed August 29, 1916. Serial No. 117,405.

To all whom it may concern:

Be it known that I, JOSEPH C. MYERS, a citizen of the United States of America, residing at the town of Colonie, in the county 5 of Albany and State of New York, have invented certain new and useful Improvements in Window-Sashes, of which the following is a specification.

My invention relates to window sashes, 10 and the object of my invention is to provide a window sash in which the glass may be removed and screens placed where the glass has been, and the sash may be taken out of the frame without the removal of the stops; 15 together with such other elements and combinations as are hereinafter more particularly set forth and claimed.

I accomplish these objects by means of the mechanism illustrated in the accompanying drawings, in which:

Figure 1 is a side elevation, partly in section, of a window sash.

Fig. 2 is a plan view showing the different positions of a window sash.

Fig. 3 is a section along the lines, 1—1, on Fig. 1, showing the cut-outs for fingers for taking out the glass or screens.

Fig. 4 is a perspective view of the cradle and roller.

Fig. 5 is a perspective view of the spring and top piece showing the lug.

Fig. 6 is a section along the lines, 2—2, on Fig. 1, showing one method of fastening the guide lug for the spring and roller.

Fig. 7 is a section along the lines, 2—2, on Fig. 1, showing another method of fastening the guide lugs for the spring and roller.

Fig. 8 is a section along the lines, 3—3, on Fig. 2, showing one method of fastening the lug piece, spring case and spring together.

Fig. 9 is a section along the lines, 3—3, on Fig. 2, showing another method of fastening the lug piece, spring case and spring together.

Similar letters refer to similar parts throughout the several views.

It is often convenient to remove a sash from a window frame for the purpose of cleaning the glass, thus preventing the necessity of sitting or standing on the window sill on the outside of a house. It is also convenient to have a window sash from which the window glass may be easily removed and replaced by a screen through which air may 50 pass.

I have provided a means for accomplish-

ing these results without the removal of the stops usually placed in a window frame for holding the sash in place, and which may be inserted in any window frame without 60 changing the construction of the frame. My invention is simple in its construction and operation and may be made with little expense.

The sash, A, is provided with a groove, 65 B, through which the glass or screen, C, may be inserted. I preferably cut out the side of the frame at D, D, to permit the operator to take hold of the glass or screen, whichever may be placed therein, for the 70 purpose of drawing it out or fitting it properly in position. The sides of the sash through which the slotted opening, B, is cut are preferably beveled as shown at E, E. On each side of the sash I place the strips, 75 G, G, which are adapted to engage the window frame passing between the stops in the place usually occupied by the window sash in an ordinary window. These strips are pivoted to each end and near each edge of 80 the sash and are beveled along the sides to engage the beveled sides, E, E, of the sash. For the purpose of arranging for this pivoting of the strips, G, G, for causing them to be held constantly in close contact with the 85 sash when the sash has been placed in the window frame, I place into the sash, A, at each end near each side thereof, a bracket, H, provided with a curved slot, h, and a spring, J. Each of the strips, G, has at each 90 end a plate, K, carrying a depending lug, k, and an opening for a pivot screw, L. The plate is fastened to the strip by means of a pin passing through the opening, m, and the pivot, M, passes through the opening, L, the 95 depending lug, k, reciprocating in the curved opening, h, in the bracket, H. The spring, J, has one of its arms resting against the lug, k, in the bracket, H; the other arm resting against the side of the bracket in 100 such position that when the strip, G, is moved as shown at the left of Fig. 2, in which position it is placed in order to enter the space between the stops in the window frame, the spring, J, will become contracted 105 as is shown in Fig. 2.

In order to cause the window to be operated up and down easily, I place the rollers, N, N, on each side thereof and arrange for 110 causing them to engage positively the side of the window frame. I accomplish this by mounting the roller, N, in a cradle, O, the

trunnions, *n*, on the roller fitting into the openings, *o*, *o*, in the sides of the cradle. The cradle is placed in the strip, *G*, with the roller, *N*, protruding from an opening in said strip. The cradle, *O*, is held in the strip, *G*, by means of the screws or pins, *s*, *s*, which pass through the openings, *s'*, *s'*, in the cradle and are secured to the strip, *G*, as shown at the left of Fig. 1. The spring, *S*, *S*, rests against the side, *g*, of the strip, *G*, and also against the upper surface, *i*, *i*, of the cradle, the resiliency of the spring tending to force the cradle away from the side, *g*, of the strip and project the roller, *N*, through the opening in the side, *b*, of the strip, *G*.

In Fig. 7 I show the position of the cradle when the spring is partly contracted.

I do not wish to limit myself to the exact construction as shown, of the various parts, or to the number of rollers used.

What I claim as my invention and desire to secure by Letters Patent is:

1. The combination of a window sash

having a strip adapted to engage the side thereof; a plate attached to said strip; a projecting lug on said plate; a pivoted bolt passing through said plate and said sash; a bracket in said sash provided with a curved slot into which said lug projects; and a spring in said bracket adapted to engage said lug and the side of said bracket, arranged so that a rotary movement of the strip will tend to contract the spring.

2. The combination of a window sash having a strip adapted to engage the side thereof; a plate attached to said strip; means for pivoting said plate to the sash; and a spring mounted in connection with said plate and said sash, arranged so that a rotary movement of the strip will tend to contract the spring, substantially as described.

In testimony whereof I have affixed my signature in the presence of two witnesses.

JOSEPH C. MYERS.

Witnesses:

FREDERICK W. CAMERON,
BEULAH CARLE.
